UNITED STATES PATENT OFFICE.

RICHARD MILLER, OF NEW BERLIN, OHIO.

BOW-REST FOR VEHICLE-TOPS.

1,168,324.

Specification of Letters Patent. Patented Jan. 18, 1916.

Application filed November 3, 1913. Serial No. 798,800.

To all whom it may concern:

Be it known that I, RICHARD MILLER, a citizen of the United States, residing at New Berlin, in the county of Stark and State of Ohio, have invented a new and useful Bow-
5 Rest for Vehicle-Tops, of which the following is a specification.

My invention relates to devices for supporting and securely holding the folded
10 tops of vehicles, and while especially adapted for use on automobiles it has other useful applications, as will be readily apparent.

The objects of the invention are to generally improve the construction of devices
15 of the character mentioned, to provide a bow rest which will be compact and substantial, convenient in use, inconspicuous, having no parts liable to rattle and adapted to firmly and securely bind the bows of the
20 top together, the operation of fastening and unfastening the binding means requiring but an instant.

Further important objects are to provide a construction which may be readily and
25 firmly connected to the bracket irons or supports of the vehicle and to so form the parts of the device that they may be easily and cheaply made.

These objects, together with other objects
30 readily apparent to those skilled in the art, may be attained by the construction illustrated in the accompanying drawings, although the invention may be embodied in other forms, the construction illustrated being chosen by way of example.

In the drawings Figure 1 is a side elevation of the rear portion of an automobile provided with a bow rest of my invented construction. Fig. 2 is a perspective view of
40 one form of the bow rest. Fig. 3 is an end elevation of the bow rest, showing the position of the bows of a folded top in dotted lines. Fig. 4 is a vertical, longitudinal section through the bow rest, without the binding strap, taken on the line 4—4 of Fig. 3. Fig. 5 is a transverse vertical section, taken at right-angles to the plane of the section in Fig. 4, and showing the rest as connected to the bracket iron of a vehicle, also showing
45 the binding strap. Fig. 6 is a perspective view of another form of bow rest embodying my invention. Fig. 7 is a top view of the bow rest casting showing the hollow inter-
rior. Fig. 8 is a transverse section through a bow rest of the type shown in Fig. 6, 55 showing the movement of the binding lever by dotted lines. Fig. 9 is an end view of a bow rest of the type shown in Fig. 6, illustrating the position of the parts when not employed to support the bows of the top. 60 Fig. 10 is a perspective view of the binding lever. Fig. 11 is a fragmentary perspective view illustrating the construction of the binding lever receiving heads. 65

Throughout the several views similar reference numerals indicate similar parts.

More specifically describing the constructions disclosed in said drawings, the numeral 1 indicates the rear portion of an automobile provided with a top 2 having bows 70 3. The automobile is provided, as usual, with the bracket iron 4 to which is attached the bow rest 5.

The bow rest comprises a lower supporting member 6, preferably formed of a casting, and a binding member 7, preferably formed of a strap. The supporting member is provided with the bow receiving portion 8 preferably provided at its front and rear ends with horizontally disposed, cylindrically concaved surfaces 9 adapted to generally conform to the shape of the lowermost bow of the folded top. Formed integrally with the bow receiving portion is the bracket attaching portion 10, which forms a 75 central, hollow depressed extension, in the side walls of which are the opposite bracket receiving apertures 11 which are preferably of the form illustrated in the drawings, the lower portions of said apertures being rounded, and the upper portions extended into angular notches 12 having straight edges 13 and 14 arranged at an angle to each other and meeting each other in the median line at 80 15. At the extreme lower part of the portion 10 is an integral boss 16 in which a central, vertically disposed set screw 17 is arranged and adapted to screw into the interior of the portion 10 and into contact with the bracket iron 4. Said bracket iron is 85 90 preferably round in cross section, as illustrated in Fig. 4, and in attaching the supporting member to the said iron the straight edges 13 and 14 of the two bracket receiving apertures will bear upon the upper curved 100 105 surface of said iron, while the set screw 17

will contact with the lower, curved surface of said iron, thus giving a five-point contact as between the supporting member and iron 4, which is well adapted to maintain the supporting member in true position and form a firm and substantial connection.

Formed integrally with the bow receiving portion 8 are the upwardly extending, relatively flared inner and outer binding-member-attaching portions 18 and 19, respectively, which portions may be of different specific constructions as will presently appear. It should be here pointed out, however, that the supporting member may be cast in one piece without the use of any core, the shape of the member permitting the casting of the bracket receiving apertures 11 in the downwardly converging side walls of the portion 10.

For the purpose of preventing chafing of the lowermost bow of the folded top the lining 20, preferably formed of leather, is arranged upon the surfaces 9 of the bow receiving portion, and extends across the open space 21 on the interior of the portion 10, but above the top of the bracket iron 4, as clearly illustrated in the drawings. Said lining may be attached to the bow receiving portion by the rivets 22, extending through the apertures 23 in the supporting member, and the upper heads of which are countersunk into the lining 20 sufficiently so as not to come into chafing contact with the lowermost bow.

The binding member 7, preferably consisting of a strap, has one end permanently attached to the inner binding-member-attaching portion 18, which is provided with an attaching bar 24 for the purpose and said binding member is of appropriate length to extend up and over the uppermost bow of the folded top and has its other end detachably and adjustably connected to the outer binding-member-attaching portion 19. In the drawings I have shown two modes of accomplishing such adjustable and detachable connection. In the form of device illustrated particularly in Figs. 2, 3, 4 and 5 the binding strap 7 is provided at its free end with a series of buckle tongue apertures 25, and the outer binding-member-attaching portion 19 is provided with a buckle bar 26, a tongue bar 27 and a buckle tongue 28 pivotally connected to the bar 27 and having its free end bearing against the bar 26, thus providing a rigidly mounted buckle for the reception of the free end of the strap 7. In Fig. 5 is clearly illustrated the buckle attachment of the free end of the strap 7 and it will be understood that the operator may draw said strap down as tightly upon the folded bows as may be desired and insert the tongue 28 into the corresponding aperture 25.

In the form of the device illustrated in Figs. 6, 7, 8 and 9 the outer binding mem-

ber-attaching portion 19 is provided with the upwardly and outwardly extending, spaced binding lever receiving heads 29 which, on their inner sides, are provided with the inverted recesses 30. The binding lever is formed with the spaced arms 31 provided at their upper ends with the outwardly projecting lugs 32 which are adapted to be received into the recesses 30. Midway between the ends of the arms 31 is a front cross bar 33, and a similar front cross bar 34 is arranged at the extreme ends of the arms 31 opposite the ends on which the lugs 32 are arranged. Intermediate the bars 33 and 34 is a back cross bar 35 extending between the arms 31 and provided with a forwardly projecting lug 36. The free end of the strap 7 is provided with a series of apertures 37, and the binding lever is connected to said strap by extending said strap between the front bars 33 and 34 and the back bar 35 and arranging the lug 36 in the desired aperture 37. In binding the bows of the folded top upon the supporting member 6 the strap 7 is extended up and over the uppermost bow of the folded top and the lugs 32 are then arranged in the inverted recesses 30, the free end of the binding lever and strap 7 being outwardly arranged, as shown in dotted lines in Fig. 8. To closely bind the bows and fasten them in place it is then only necessary to press the free end of the binding lever downwardly against the side of the bracket attaching portion 10, as illustrated in full lines in Fig. 8, whereupon the portion of the strap 7 extending from the binding lever to the uppermost bow will be moved inwardly beyond the axis of pivotal connection produced by the lugs 32 in the recesses 30. By reason of this "over the center" arrangement, therefore, the bows will remain in tightly bound condition until it is desired to release them, when an outward pull upon the free end of the strap 7 and binding lever will so slacken the strap 7 as to permit the lugs 32 to be easily freed from the recesses 30. When the top is not folded and it is desired to carry the device in the neatest manner the strap 7 may be folded upon itself and the binding lever arranged in the vertical position intermediate the portions 18 and 19, illustrated in Fig. 9. The folded portion of the strap 7 may then be extended through the opening 38 in the portion 19, as illustrated in Fig. 9, whereupon it will be found that the parts will be carried in such position without rattling or loosening, regardless of the vibration or movement of the vehicle.

While the bow rests for vehicle tops shown and described disclose the best forms in which I have contemplated embodying my invention, I do not desire to be limited to the details so shown and described, for many changes may be made as circumstances re-

quire or experience suggests without departing from the spirit of the invention, within the scope of the appended claims.

I claim;—

- 5 1. In a bow rest for vehicle tops, a supporting member formed of a single casting provided with upwardly disposed, concave bow receiving portions provided at their sides with upwardly and outwardly extending binding-member-attaching portions, said casting in its lower part formed with an integral, hollow bracket attaching portion opening at the top intermediate said bow receiving portions with a flared opening, a lining attached to said bow receiving portions, extending across said flared opening and constituting a cushion for receiving the lowermost bow of a folded top, said hollow bracket attaching portion provided with 10 alined bracket receiving apertures in the opposite lateral walls of the same, said apertures having angular notched extensions in their upper portions, and a median, vertically disposed set screw extending through 15 the bottom wall of said bracket attaching portion and adapted to engage the lower side of a bracket iron extended through said alined apertures, a binding member con-
- 20 nected to said binding-member-attaching portions and means for adjustably connecting one end of said binding member to one of said binding-member-attaching portions. 30
- 25 2. A bow rest for vehicle tops comprising a supporting member provided with integral outwardly extending binding-member-attaching portions, a binding member having one end permanently connected to one of said attaching portions, the other attaching portion extending upwardly and outwardly and provided with inverted recesses, and a binding lever connected to the other end of 35 said binding member, having lugs adapted to be removably seated in said inverted recesses, and said lever, when said lugs are so seated, adapted for pivotal movement to 40 tighten or loosen said binding member, and said lever adapted to normally retain the position assumed when said binding member is fully tightened. 45

In testimony that I claim the above I have 50 hereunto subscribed my name in the presence of two witnesses.

RICHARD MILLER.
